Patented Aug. 30, 1921.

UNITED STATES PATENT OFFICE.

JOHN COFFEY, OF BOSTON, MASSACHUSETTS, ASSIGNOR TO UNITED SHOE MACHINERY CORPORATION, OF PATERSON, NEW JERSEY, A CORPORATION OF NEW JERSEY.

STITCHED BUTTONHOLE.

1,389,027.

Specification of Letters Patent. Patented Aug. 30, 1921.

Application filed November 27, 1918. Serial No. 264,321.

To all whom it may concern:

Be it known that I, JOHN COFFEY, a citizen of the United States, residing at Boston, in the county of Suffolk and State of Massachusetts, have invented certain new and useful Improvements in Stitched Buttonholes; and I do hereby declare the following to be a full, clear, and exact description of the invention, such as will enable others skilled 10 in the art to which it appertains to make and use the same.

The invention relates to stitched buttonholes.

The object of the invention is to improve 15 and strengthen the bar of buttonholes in which the stitches at the end of the seam overlie the stitches at the beginning of the seam in line with and beyond the buttonhole slit to form what is known as a "fly" bar. 20 Buttonholes of this type are frequently provided with a stay cord covered by the stitches of the overseam, and a further object of the invention is to more securely anchor this cord at the end of the seam. With these 25 objects in view, the invention comprises a stitched buttonhole the overseam of which turns through substantially a complete cycle, and has its initial and final end portions superposed in line with and beyond the end 30 of the buttonhole slit. The ends of the overseam thus form a fly bar, the stitches of which may cross each other to strengthen the bar, and the needle holes of which may be so distributed that they do not weaken 35 the fabric. The initial and final ends of the seam comprised in the bar preferably turn through approximately 90° each, particularly in stayed buttonholes, since both ends of the stay cord may be turned with the 40 seam so that they are more securely held against endwise movement, and more efficiently resist any lengthwise pull due to strain upon the eye end of the buttonhole. The turning of the ends of the seam also 45 enables the stitches along its superposed ends to be symmetrically and oppositely arranged at substantially equal angles to the line of the buttonhole slit, so that they cross each other substantially in line with the slit 50 and strengthen the bar.

The invention will be understood from an inspection of the accompanying drawings and the following detailed description of the buttonhole illustrated therein.

55 In the drawings, Figure 1 is a plan view

on an enlarged scale showing the upper side of a stitched buttonhole embodying the invention in its preferred form, and Fig. 2 is a view of the under side of the bar end of the buttonhole.

As shown in the drawings, the buttonhole comprises a buttonhole slit 2 formed in a fabric 4 and an overseam 6 extending along the edge of the slit and beyond the bar end of the buttonhole. The beginning or initial 60 end of the seam is in line with and extends some distance beyond the end of the buttonhole slit, the line of the slit being approximately midway of the bight of the seam. The final end of the seam is also in line 65 with and extends an equal distance beyond the end of the buttonhole slit, so that it overlies the initial end portion to form the fly bar 8. As shown, the first stitch 10 of the seam is in line with and nearly parallel to 70 the buttonhole slit. The succeeding stitch 12 is at a greater angle to the line of the slit, and the outer end of the stitch is preferably 75 in transverse alignment with the outer end of the first stitch, since by this arrangement 80 a square ended and finished bar is formed. The next stitch 14 is at a still greater angle to the line of the slit, being nearly at right angles thereto, and its outer end is in substantial lengthwise alignment with the outer 85 end of the stitch 12. This stitch is the first stitch of that part of the seam which extends substantially lengthwise of the buttonhole slit. The initial end of the seam thus turns through approximately 90°, and in 90 case a stay cord 16 follows and is covered by the seam, it also turns through substantially 95 90°, so that it has a comparatively sharp turn as it passes under the initial stitches of the seam, and is therefore more securely anchored and held in place against lengthwise movement. The angularity of the stitches succeeding the stitch 14 changes but slightly, while the seam bends laterally at 18 until the inner ends of the stitches 100 pass over the edge of the buttonhole slit. The buttonhole slit is provided with an eye 20 at its outer end, and the seam turns through substantially 180° in passing about the eye, the angularity of the stitches also 105 changing so that they extend radially of the eye and are symmetrically but oppositely arranged on opposite sides of the buttonhole slit. Immediately beyond the inner end of the buttonhole slit the seam bends inward at 110

22 so that beyond the end of the slit it overlies and substantially registers with the initial part of the seam. The stitches in the superposed end portions of the seam are 5 symmetrically and oppositely arranged so that they cross each other substantially in line with the buttonhole slit. The final end of the seam turns through substantially 90°, the arrangement of the three final stitches being 10 the reverse of the first three stitches, so that a series of cross and radiating stitches is formed across the end of the bar which serves to strengthen the bar as well as to give it a more finished appearance. The 15 final end of the stay cord which follows the seam also turns through substantially 90° and therefore has at its end a comparatively sharp turn which securely anchors this end of the cord against endwise movement. 20 While it is preferred to arrange the stitches in the bar substantially as shown and described it will be understood that this arrangement is not essential to the broader features of the invention, and may be varied 25 or modified as found desirable or best suited to the conditions under which the buttonhole is to be used, or as best suited for manufacture upon the machine which is to be utilized in making the buttonhole. 30 Having explained the nature and object of the invention, and specifically described one form of buttonhole in which it may be embodied, what is claimed is:—

1. A fabric having an eye-ended stitched 35 buttonhole comprising an overseam which

turns through substantially 180° at the eye and through substantially 90° at its initial end and substantially 90° at its final end and has said ends superposed in line with and beyond the end of the buttonhole slit. 40

2. A fabric having an eye-ended stitched buttonhole comprising an overseam which turns through approximately 180° at the eye and through substantially 90° at its initial end and substantially 90° at its final 45 end and has said ends superposed in line with and beyond the end of the buttonhole slit, and a stay cord following the seam and covered thereby.

3. A fabric having an eye-ended stitched buttonhole comprising an overseam having its initial stitch located in the body of the fabric beyond the end of the buttonhole slit in line with and approximately parallel to the same, the angle of the immediately following stitches progressively increasing until approximately at right angles to the buttonhole slit, the seam then bending laterally until the inner ends of the stitches pass over the edge of the slit, then extending along the 50 first side of the slit, turning about the eye, then extending back along the second side of the slit, then bending laterally beyond the end of the slit to overlie and substantially register with the initial end of the seam, the 55 arrangement of the final stitches of the seam being substantially the reverse of the initial stitches.

JOHN COFFEY.
